Patented Jan. 15, 1918.

2 SHEETS—SHEET 1.

The image contains two technical drawings of a shoe assembly and a sole component.

Fig. 1. This drawing shows a side view of a shoe assembly. The shoe has a curved upper part (3) and a rectangular toe cap (2). A vertical strap (1) is attached to the upper part, featuring a rectangular buckle (8) and a circular buckle (12). A small rectangular label (13) is attached to the strap. A vertical rod (9) is attached to the upper part, with a circular cap (42) and a cylindrical component (43) attached to its top. A curved strap (15) is attached to the upper part, ending in a hook (17). A label (33) is attached to the side of the upper part. A label (34) is attached to the toe cap (2). A label (39) is attached to the side of the upper part, near the buckle area.

Fig. 2. This drawing shows a sole component. It features a curved upper part (3) and a rectangular toe cap (2). A vertical strap (1) is attached to the upper part, with a rectangular buckle (5) and a circular buckle (30) attached to it. A vertical rod (9) is attached to the upper part, with a circular cap (42) and a cylindrical component (43) attached to its top. A curved strap (15) is attached to the upper part, ending in a hook (17). A label (31) is attached to the side of the upper part, near the buckle area. A label (33) is attached to the toe cap (2). A label (39) is attached to the side of the upper part, near the buckle area.

UNITED STATES PATENT OFFICE.

GUSTAV W. E. HOHME, OF CASTOR, ALBERTA, CANADA.

SHOE-STRETCHER.

1,253,973.

Specification of Letters Patent. Patented Jan. 15, 1918.

Application filed June 20, 1917. Serial No. 175,889.

To all whom it may concern:

Be it known that I, GUSTAV W. E. HOHME, a subject of the King of Great Britain, residing at Castor, in the Province of Alberta and Dominion of Canada, have invented new and useful Improvements in Shoe-Stretchers, of which the following is a specification.

My invention relates to shoe stretchers and has for its objects; first, to provide a shoe stretcher which not only stretches the last of the shoe laterally, but will stretch the last longitudinally also; second, to provide a shoe stretcher which will stretch the last longitudinally, and which may be easily placed in a shoe; and thirdly, to provide a shoe stretcher which is easily and quickly adjustable in all directions.

With these and other objects in view which will be hereinafter fully described and particularly pointed out in the claims, the invention consists in the novel construction and arrangement of parts illustrated in the accompanying drawings forming a part of this specification, in which:

Figure 1 is a side elevation of a shoe stretcher embodying my invention, a shoe being shown in dotted lines,

Fig. 2 is a top plan view of the same, Fig. 3 is a longitudinal section on the line *a—a* of Fig. 1,

Fig. 4 is a vertical section through the center of the stretcher.

Like characters of reference indicate like parts in the various views.

In the drawings 1 designates the rear section of the stretcher, which together with a longitudinally adjustable heel 2 comprise the shoe heel engaging portion of the stretcher. The front section of the stretcher comprises two longitudinal last members 3 having the inner sides 4 thereof abutting, and having corresponding cavities 5 formed on said abutting inner sides 4. A hinge plate 6 is secured upon the front surface of the rear section, by means of screws 7 and has vertical extending hinge bearings 8 formed on either side thereof. Hinge ears 9 are secured to the rear ends of respective last members 3 and have vertical hinge bearings 10 formed at their outer sides and adapted to register with respective hinge bearings 8. Pivotal pins 11 are engaged by respective hinge bearings 8 and 9 whereby the last members are hingedly connected to the rear section for lateral

swinging movement. Forwardly extending projections 12 are formed on the side edges of the hinges 9 and are secured upon respective sides of the last members 3 by means of screws 13, screws 13 also securing the main portion of the hinges to the rear surface of the last members. By means of the construction of the hinge plate 6 and the hinges 9 the last member 6 have a substantial hinge connection with the rear surface which is well adapted to stand the hard usage to which a device of this character is subject. A threaded nut 14 is mounted upon the rear side of the hinge plate 6 and an actuating screw 15 passes through a hole 16 in the rear section, and is screw threaded into said nut 14 and projects into the cavities 5, a handle 17 being provided at the rear end of said screw for convenient manual manipulation thereof. The front end of actuating screw 15 is ball shaped, as designated at 19, and a wedge 20 has its rear end provided with a cavity 21, which embraces said ball shaped end 19 and forms a ball and socket connection therewith. The wedge 20 tapers toward a point at its front end and terminates in a longitudinally extending tip 22. Laterally disposed rearwardly facing shoulders 23 are formed at the rear end 85 of the wedge for purposes hereinafter described.

Each cavity of the last members 3 is provided with a flat spring 24 which has its rear ends secured to the respective last member by means of a screw 25. Each spring slants inwardly toward the front end of the last member and has the front thereof bent laterally, as designated at 26, and abutting the adjacent wall of the cavity. The middle 95 portions of the springs, which are slanted inwardly toward the front end, form cam surfaces 27 which are engaged by the tapered portion of the wedge 20 to extend the last members. A wedge 28 is disposed in back of 100 each spring and may be adjusted in various positions relative thereto by means of a vertical longitudinally extending slot 29 formed in each last and extending upwardly from the cavity therein to the surface of the last, 105 and a headed screw 30 which projects down through each slot and is screw threaded into its respective wedge 28. The surface of each last is countersunk about the slot 29, so that the head of the screws 30 do not 110 project above the surface of their respective last, as designated at 31.

Corresponding channels 32 are formed at the front end of each cavity 5 and extend forwardly to the front surface of their respective lasts. A toe 33 is provided which 5 has a rearwardly extending shank 34 adapted to be engaged by said channels, and which is adapted to be clamped in said channels when said lasts are in their retracted position. The rear end of the shank 34 has 10 a bottomed hole 35 formed therein adapted to snugly receive the end of the tip 22 of the wedge.

A heel 36 is provided which has a forwardly extending rack bar 37 mounted 15 thereon. The rack bar 37 is mounted for sliding movement within a slide 38 formed in the rear section 1. A vertical shaft 39 is mounted for rotation in said rear section 40 and has a pinion mounted thereon within 20 a recess 41 of said rear section, which engages the rack bar 37. The shaft 39 extends upwardly and terminates in a handle 42, and a ratchet wheel 43 is mounted thereon adjacent the upper surface of the rear 25 section. A pawl 44 is pivotally mounted upon said rear section and is adapted to engage the teeth of the ratchet wheel 43, said pawl and ratchet wheel serving to secure the heel 36 in any position against inward 30 movement thereof.

Transverse shoulders 45 are formed in respective cavities 5 at the rear end thereof and are engageable with respective shoulders 28 of the wedge when the actuating 35 screw 15 is rotated to retract the wedge to its extreme rear position, and by reason of this engagement the last members 3 may be clamped together. As the actuating screw 15 is rotated to move the wedge 20 forward, 40 said wedge engages the cam surfaces 27 of the springs 24 and the last members tend to spring apart at this point. Upon further rotation of the actuating screw 15 to move the wedge 20 farther forward, the springs 45 24 will be depressed until said springs abut their respective wedges 28 whereupon a solid connection is established between the wedge and the last members and a force, up to the capability of the structure, may be exerted upon the last members by the wedge 50 to extend the same. This initial resilient connection between the wedge and the last members is especially important when the last is being positioned in the shoe preparatory to stretching the same, as it may be first positioned in the shoe with the last clamped together, and the spring may be 55 then released and the stretcher pushed to proper position, said resilient connections 60 serving to aid in properly positioning the same without the danger of improperly stretching the shoe by initially extending the wedge members with a solid wedge connection as the stretcher is being positioned 65 in the shoe, as is the case in shoe stretchers

now in vogue which have no resilient connection between the last and the extending means as hereinbefore disclosed.

The toe 33 serves to stretch the shoe longitudinally, and it will be noted in this regard that said toe may be removed to stretch the last laterally. In stretching a shoe longitudinally the shank of the toe is inserted into the inclosure of the channels 32 and the wedge retracted to clamp the 75 last together, the channels 32 are so formed as to clamp the shank 34 as the lasts are clamped together and serve to hold the toe in the stretcher as the stretcher is being inserted into the shoe. This clamping action 80 also prevents the rotation of the toe, which is usually oval in shape as shown. When the structure is inserted into the shoe the wedge is moved forward slightly to disengage the shoulders thereof from the shoulders of the cavities and to engage the springs 24. At this point the last extends slightly under the influence of the springs and engages the sides of the shoe. The last may be now easily positioned properly within the 90 shoe, and the heel 36 is then moved outwardly to abut the rear of the shoe. The actuating handle 17 is then actuated to move the wedge forwardly and the tip pushes the toe, and the shoe is stretched thereby between the heel 36 and the toe 33. If it is desired to stretch the shoe laterally as well as longitudinally the wedges 28 are properly 95 adjusted and the stretcher manipulated as described above.

I wish to state that the shoe stretcher may be made wholly of metal, part wood and part metal, or can be made of some suitable compressed material. The rack bar 37 for driving out the heel, can be made either as 105 described or may be in the nature of a double rack bar, which is actuated by a threaded nut, the said nut being in the shape of a wheel, when the said wheel is countersunk, and half threaded a threaded shaft fit in 110 the rim of the wheel to act as an endless screw, the said threaded shaft to be operated in the manner as set forth in the specification.

Having thus fully described my invention, I claim:—

1. In a shoe stretcher, the combination of a last having a longitudinally extending hole at the front end thereof, a toe adapted for movement in said hole, means for projecting said toe forwardly, and means operable with said first mentioned means and adapted to clamp said toe in said hole when the toe is retracted.

2. In a shoe stretcher, the combination of 125 abutting last members having corresponding channels in the abutting surfaces thereof, means for clamping said last members in retracted position, and a toe adapted to be clamped in said channels when said last 130

members are held in retracted position and having operable relation with said means whereby the toe is projected forwardly when said means is moved to allow said last members to extend, and means for actuating said first mentioned means.

3. In a shoe stretcher, the combination of abutting last members hinged together at their rear ends and having corresponding 10 cavities in the abutting surfaces thereof and having transverse forwardly facing shoulders in said cavities, a movable member operable within said cavities and having laterally disposed rearwardly facing shoulders engageable with said transverse shoulders and having a forwardly extending tip, a toe engageable with said tip, and means for actuating said movable member, said cavities having forwardly extending channels adapted to clamp said toe therebetween when said last members are in their retracted positions.

4. In a shoe stretcher, the combination of a rear section, abutting last members hinged 25 to said rear section and having corresponding cavities in the abutting surfaces thereof, a movable member operable within said cavities and having rearwardly facing laterally disposed shoulders thereon, and having a 30 forwardly extending tip, a toe engageable with said tip, and an actuating screw threaded in said rear section and having operable connections with said movable member, said cavities having transverse 35 shoulders engageable with said lateral disposed shoulders of the movable member and having forwardly extending channels adapted to clamp said toe therebetween when said last members are in their retracted positions.

5. In a shoe stretcher, the combination of abutting last members hinged together and having corresponding cavities in their abutting surfaces, said cavities being formed 45 with cam surfaces and transverse shoulders, a wedge member operable within said cavity and engageable with said cam surface and having laterally disposed shoulders, a toe having operable connection with said wedge, 50 said cavities being formed with forwardly extending channels adapted to clamp said toe when said last members are in retracted position, and means for actuating said wedge member.

55 6. In a shoe stretcher, the combination with a wedge, of a movable member, a flat spring secured on said movable member and forming a cam surface engageable with said wedge, and a second wedge mounted on said

movable member in back of said spring and 60 adapted to reinforce said spring member.

7. In a shoe stretcher, the combination of abutting last members having corresponding channels in the abutting surfaces thereof, means for holding said last members in 65 retracted positions, a toe adapted to be clamped in said channels when said last members are held in retracted positions, and having operable relation with said means whereby the toe is projected forwardly when 70 said means is moved to cause said last members to extend, a spring means adapted to extend said last members when they are released by said means, and means for actuating said first mentioned means. 75

8. In a shoe stretcher, the combination of abutting last members hinged together at their rear ends and having corresponding cavities in the abutting surfaces thereof, said cavities being formed with transverse forwardly facing shoulders, a flat spring secured in each cavity and forming a cam surface, a wedge operable within said cavities and having laterally disposed rearwardly facing shoulders, a second wedge 85 mounted on each last member in back of respective springs and adapted to reinforce said springs, a toe in operable relation with said wedge and adapted to be projected forwardly by the movement of the same, said 90 cavity having forwardly extending channels adapted to clamp said toe when said last members are in retracted positions, and means for actuating said wedge.

9. In a shoe stretcher, the combination of a rear section, abutting last members hinged to said rear section and having corresponding cavities in the abutting surfaces thereof, said cavities having forwardly facing transverse shoulders, a flat spring secured 100 in each cavity and forming a cam surface, a wedge operable within said cavities and having laterally disposed rearwardly facing shoulders and having a forwardly extending tip, a second wedge mounted on each 105 last member in back of said respective springs and adapted to reinforce said springs, a toe engageable with said tip and adapted to be projected forwardly by the movement of the same, said cavity having 110 forwardly extending channels adapted to clamp said toe when said last members are in retracted positions, and an actuating screw threaded into said rear section and operably connected with said wedge. 115

In testimony whereof I affix my signature.

GUSTAV W. E. HOHME.
